CLAIM

The ornamental design for a wireless router, as shown and described.

DESCRIPTION

FIG. 1 is a top perspective view of a wireless router showing our new design;

FIG. 2 is a Bottom Perspective View thereof;

FIG. 3 is a Top View thereof;

FIG. 4 is a Bottom View thereof;

FIG. 5 is a Back View thereof;

FIG. 6 is a Front View thereof;

FIG. 7 is a Left Side View thereof; and,

FIG. 8 is a Right Side View thereof.

The broken lines shown in the drawings are included for the purpose of illustrating structural environment and form no part of the claimed design.
